CRASH HELMET

Ray W. Lipper, Newport Beach, Calif., assignor to Center
Line Tool Corporation, Santa Fe Springs, Calif.

Filed Nov. 20, 1974, Ser. No. 525,569

Term of patent 14 years

Int. Cl. D2—03

U.S. Cl. D2—231

FIG. 1 is a front elevation view of a crash helmet showing my new design;

FIG. 2 is a left elevation view thereof, the right side is identical to the left side; and

FIG. 3 is a rear elevation view thereof.

I claim:

The ornamental design for a crash helmet, as shown and described.
